Wesley G. Barr
ATTORNEY

UNITED STATES PATENT OFFICE.

HAROLD W. WILLIAMS, OF WILKINSBURG, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed September 8, 1923. Serial No. 661,538.

To all whom it may concern:

Be it known that I, HAROLD W. WILLIAMS, a citizen of the United States, and a resident of Wilkinsburg, in the county of Allegheny and State of Pennsylvania, have invented a new and useful Improvement in Motor-Control Systems, of which the following is a specification.

My invention relates to motor-control systems and it has particular relation to such systems of control as are employed in connection with elevators, machine tools and similar machines.

The object of my invention is to provide means for controlling the speed and the torque of an alternating-current motor of the two-speed type commonly employed in elevator service and having separate low and high-speed windings.

My invention is more particularly applicable to the control of a two-speed motor of the well-known squirrel-cage type.

In the operation of alternating-current motors of the type herein described, it is common practice to start the motor by connecting its low-speed winding to the source of power and thereafter transfer directly to the high-speed winding, with or without resistors in circuit therewith.

In such systems, some difficulty has been experienced in obtaining smooth operation. In my system of control, I propose to start the motor by means of its low-speed winding. Next, in transition, I connect the high and low-speed windings in parallel relation and provide means for ensuring a relatively weak excitation of the low-speed windings. Next, the low-speed windings are shunted and the excitation of the high-speed windings is increased to its maximum value.

To effect deceleration of the motor, the speed windings are first connected in the previously named parallel relation, after which the high-speed windings are deenergized and finally the excitation of the low-speed winding is increased to obtain a minimum desirable operating speed.

My invention will be described in connection with the accompanying drawing, in which—

Figure 1 is a diagrammatic representation of a two-speed, three-phase, alternating-current squirrel-cage motor employed in connection with my invention,

Fig. 2 is a diagrammatic representation of the main circuits and apparatus embodying my invention,

Fig. 3 is a diagrammatic representation of the control circuits that are employed in the operation of the system shown in Fig. 2, and

Fig. 4 is a sequence chart indicating the operation of switches employed in Fig. 2.

Referring to the drawing, a two-speed alternating-current motor 1 is provided with low-speed primary windings 2 and high-speed primary windings 3. These windings are connected in series relation with a plurality of reactors 4 and 5, which are respectively employed for low-speed and for high-speed operation. Resistor sections 6 are arranged for connection in circuit with the high-speed windings 3 through a switch 7. A three-pole switch 8 provides means for shunting the high-speed windings 3 and rendering the low-speed windings 2 effective. Double-pole reversing switches 9 and 10 are employed in the customary manner. Portions of the "low-speed" reactors 4 may be shunted by a double-pole switch 11 that is provided with a retarding device 12.

Also, a double-pole switch 13 is arranged for shunting resistor sections 6. This switch is also provided with retarding means. Both switches 11 and 13 are retarded only in closing. The various switches are operated by means of a reversible master switch 23 of a familiar type having a plurality of operating positions *a*, *b*, *c* and *d*. A source of power supply for the motor comprises line conductors 14, 15 and 16. I have illustrated connections for a three-phase induction motor, but, of course, a two-phase motor or motors of other suitable types may be similarly employed.

Assuming the apparatus to be in its inoperative or illustrated positions, the motor 1 may be operated in an "upward" direction by actuating the master switch 23 to the right. In position *a* (see sequence chart, Fig. 4) a circuit is provided for effecting the closure of reversing switch 9 and "low-speed" switch 8. Power is then supplied to the motor windings 2, with reactors 4 in circuit therewith. If master switch 23 is maintained in position *a*, switch 11 will close to shunt a portion of reactors 4, whereby the motor is provided with sufficient torque to

start the desired maximum load. A light load may be started prior to the closure of switch 11. However, the primary object of the additional sections of reactors 4 will 5 hereinafter appear.

When the master switch 23 is actuated toward position *b*, switch 7 closes prior to the opening of switch 8, whereupon high-speed windings 3 are connected through resistor 10 sections 6 in parallel relation to low-speed windings 2. This position affords a transition period or, if desired, may serve as an operating position in which the motor operates at a speed intermediate its minimum 15 and maximum speeds, depending upon the degree of excitation of the low-speed windings 2.

When the master switch 23 is moved to position *b*, switch 8 opens and the motor 20 is further accelerated in accordance with the excitation of the windings 3. Finally switch 13 closes to shunt resistors 6, whereupon the motor operates at its maximum speed.

25 It should be noted, in connection with the foregoing description, that the motor speed-windings are at no time disconnected nor is the power supply interrupted, so that a fairly uniform torque is developed by the 30 motor in accordance with the arrangement of the reactors and resistors which are, of course, designed for limiting the currents in a well-known manner.

The motor is decelerated by returning 35 master switch 23 toward the "off" position, passing through position *a*. Switch 8 is re-closed, re-establishing the above-described parallel relation of motor windings 2 and 3 and, upon the re-opening of switch 7, the 40 high-speed windings 3 are deenergized and the motor is further decelerated, since only the low-speed windings 2 are then energized. Switch 11 starts to close but is retarded for a sufficient period, whereby the torque of 45 the motor, which is for the moment operating above its lower synchronous speed, is suitably reduced. The effect of the additional reactor sections 4, which are controlled by switch 11, is to prevent a too 50 abrupt change in the speed of the motor, occasioned by its regenerative action. Sufficient time is allowed for the closure of switch 11 so that the motor speed is first suitably reduced. Under slow speed conditions, reactors 4 have little effect upon the 55 speed regulation of the motor, so that it is, ordinarily, unnecessary to provide means for entirely shunting these reactors from the circuit. If it is desirable to operate the motor at slow speed for long periods, an additional switch may be, of course, provided to entirely shunt these reactors.

According to my invention, I am enabled 60 to accelerate and decelerate a motor having separate high and low-speed windings with-

out disconnecting these windings, whereby a fairly uniform torque is obtainable and, consequently, smooth and flexible speed control. Also, the switching arrangement is such that the line conductors cannot be short-circuited by failure of any of the speed-controlling 70 switches to function.

In the arrangement of apparatus, as illustrated in Fig. 2, it is possible to provide for a different sequence of operation and to obtain still other operating speeds as, for example, when both the high and low-speed switches 7 and 8 are open, and the motor windings are all connected in series relation. Resistors may be substituted in place of 75 reactors 4 and 5, when desirable, but I prefer to employ the arrangement illustrated, particularly for hoisting applications.

Operation of the motor in a reverse direction is obtained in a manner similar to that described above, upon the closure of reversing switch 10 in place of reversing switch 9 by the manipulation of master switch 23 to the left, through positions *c* and *d*, as will be readily understood.

I have described and illustrated my invention in simple form, but various modifications may be made therein without departing from the spirit and scope thereof.

I claim as my invention:

1. The method of accelerating an alternating-current motor having low and high-speed windings connected in series relation, which consists in shunting the high-speed windings, connecting said high and low-speed windings in parallel relation, diminishing the effect of said low-speed windings and finally shunting said low-speed windings.

2. The method of accelerating an induction motor having low and high-speed windings connected in series relation, which consists in energizing the low-speed windings, connecting said low and high-speed windings in parallel relation, lessening the effect of said low-speed windings, and finally, shunting said low-speed windings.

3. The method of decelerating an alternating-current motor having low and high-speed windings connected in series relation, which consists in connecting the low and high-speed windings in parallel relation when the effect of the low-speed windings is relatively weak, disconnecting said high-speed windings and strengthening the effect 115 of the low-speed windings.

4. The combination with an alternating-current motor having low and high-speed windings connected in series relation, and reactors alternating in position with said windings, of means for selectively shunting said windings and for connecting said windings in parallel relation without interrupting the motor circuit.

5. The combination with an alternating-

current motor having low and high-speed windings connected in series relation, and reactors alternating in position with said windings, of means for selectively shunting 5 said windings and for connecting said windings in parallel relation without disconnecting said windings.

6. The combination with an alternating-current motor having low and high-speed 10 windings connected in series relation, and current-limiting means alternating in position with said windings, of means for selectively shunting said windings and for connecting said windings in parallel relation 15 without interrupting the motor circuit.

7. The combination with an alternating-current motor having low and high-speed windings connected in series relation, and

current-limiting means alternating in position with said windings, of means for selectively shunting said windings and for connecting said windings in parallel relation without disconnecting said windings. 20

8. The combination with an alternating-current motor having low and high-speed 25 windings connected in series relation, and reactors in circuit with said windings, of means comprising said reactors for selectively shunting said windings and for connecting said windings progressively in series 30 and in parallel relation without interrupting the motor circuit.

In testimony whereof I have hereunto subscribed my name this 13th day of August, 1928.

HAROLD W. WILLIAMS.
